(57) **CLAIM**

The ornamental design for a steering handle for outboard motor, as shown and described.

DESCRIPTION

FIG. 1 is a rear, left side and top perspective view of a steering handle for outboard motor showing my new design
FIG. 2 is a front, right side and top perspective view thereof;
FIG. 3 is a right side view thereof;
FIG. 4 is a left side view thereof;
FIG. 5 is a top view thereof;

FIG. 6 is a bottom view thereof;

FIG. 7 is a rear view thereof;

FIG. 8 is a front view thereof; and,

FIG. 9 is a perspective view thereof, with environmental material shown in broken line.

The broken line showing of a motor is environmental material for illustrative purposes only and forms no part of the claimed design.

1 Claim, 8 Drawing Sheets
